UNITED STATES PATENT OFFICE.

WILLIAM J. WISWALL, OF OAKLAND, CALIFORNIA, ASSIGNOR, BY MESNE ASSIGNMENTS, TO AMERICAN SALES BOOK COMPANY, LIMITED, OF TORONTO, ONTARIO, CANADA, A CORPORATION OF CANADA.

MANIFOLDING BOOK.

Application filed May 25, 1921. Serial No. 472,341.

To all whom it may concern:

Be it known that I, WILLIAM J. WISWALL, a citizen of the United States, residing at Oakland, in the county of Alameda and State of California, have invented new and useful Improvements in Manifolding Books, of which the following is a specification.

This invention relates to record strip supplies for manifolding machines and with respect to its more specific features to supplies of the character referred to adapted for use in manifolding registering machines and especially autographic registers.

One of the objects of the invention is the provision of a practical multiple strip supply pad for machines of the character above referred to in which the effectiveness of the registering operation is increased and accuracy of registration attained.

Another object is the provision of a simple construction of supply pad wherewith much of the detail of equipping said machines with record strips is avoided; equipment with any number of supply strips easily and quickly accomplished and correct registration promoted.

Another object of the invention is the provision of a practical unitary pad composed of a plurality of record strips having printed forms and also having features adapted to promote accurate registration in said machines, the strips being associated in the pad in such manner that closely approximate registration of corresponding forms is maintained throughout the pad, any displacement of said registering features in respect to each other being constant as distinguished from a progressively increasing amount.

Among other objects of the invention may be mentioned the provision of a practical manifolding book or supply pad of such construction as to afford a maximum of economy and accuracy in manufacture; simplicity and effectiveness of manipulation; convenient for equipping the machine and adapted for the preservation of a complete record of transactions in readily accessible form.

Other objects of the invention will be in part obvious and will in part appear herein-after.

The invention accordingly comprises an article of manufacture possessing the fea-

tures, properties, and the relation of elements which will be exemplified in the article hereinafter described and the scope of the application of which will be indicated in the claims.

For a fuller understanding of the nature and objects of the invention reference should be had to the following detailed description taken in connection with the accompanying drawing, in which:

Figure 1 is a perspective view of one embodiment of the invention showing the printed forms, apertures provided therefor, and the method of assembling and folding the strips, and

Fig. 2 is a plan view of one of the strips of Fig. 1, showing the position of the respective forms with relation to each other and to the punched or apertured portions.

At this point it may be stated that the pad of the present invention is constructed to retain a plurality of connected sets of record leaves, each having printed forms, in closely approximate registry with each other regardless of whether the record strips be long or short, and while it has a variety of uses it is of special utility when used with autographic registers, particularly with such registers which have feeding means for simultaneously advancing a plurality of superposed strips over a writing tablet, the strips being rendered ineffective to advance by apertures therein.

Referring now more specifically to the drawings, the numerals 2, 3, and 6 indicate, respectively, an original, a duplicate, and a triplicate record strip, the three providing a plurality of superposed contiguous strips. There may be a greater number of strips, three sufficing for illustrative purposes. To associate the strips they may be contiguously superposed when in the extended form illustrated in Fig. 2, and then folded as one into a book, or pad. In the embodiment illustrated the three strips are simultaneously folded on the transverse fold lines indicated generally by the numerals 7, in a zig-zag manner, there being thus a longitudinal series of these lines. In this way the folds of each strip will be interengaged with those of the others so as to provide superposed sets A, B, and C, of superposed leaves connected end-to-end transversely of the fold lines.

Each of the strips 2, 3, and 6 is provided

- with a longitudinal series of printed forms and with a longitudinal series of strip registering, or form-registering apertures in fixed relation to said forms, respectively.
- 5 In the embodiment illustrated each printed form covers the greater part of a leaf, each leaf having a form, the forms on each leaf of the manifolding sets A, or B, or C being alike. For each form of a manifolding set 10 there is a form-registering aperture 5, which is preferably in duplicate, as illustrated, each such aperture being in fixed relation to its form, and this relation being the same in all the leaves, so that when the apertures 15 of superposed leaves are in registry with each other, the relevant printed forms are also in registry. The forms are longitudinally spaced apart on each strip and, as illustrated, the form-registering apertures 20 are in the same sequence as the forms and are located in the spaces between the forms and at the top end of each form controlled thereby. In this wise the form-registering apertures of each manifolding set of leaves, 25 as A, or B, or C, are disposed opposite an unapertured portion of the next adjacent superposed set, when the strips 2, 3, and 6 lie in zig-zag folded relation in the pad, and are adapted to permit said next adjacent set to be viewed through the apertures. 30 Among the results promoted by this disposition of the apertures may be mentioned the facility with which it may be determined that each manifolding set, whatever be its 35 position in the pad, contains its full number of properly colored leaves, when record strips of different color are used. For instance, if the strip 2 is white, and the strip 6 is yellow, one should find the yellow color 40 visible through the apertures looking from above in Fig. 2. If a color other than yellow appears it is an indication that the set B lacks a leaf, as for instance might result should the strip 6 have parted, or not be 45 sufficiently long to extend to the set B. Similarly on looking through the apertures 5 in the set B, the white color of the strip 2 should be seen.
- It will be noted that the form-registering 50 apertures 5 are clear of the fold lines. Inasmuch as these apertures are intended to cooperate with the feed wheels of the machine to promote registry of a set of the printed forms, and as one or more of the 55 inscribed leaves are usually separated from the strips by being torn along the fold lines, it is desirable to maintain the apertures intact notwithstanding the tearing along the fold lines. In some instances, should such 60 apertures be located in the fold lines, the tearing along such lines might even free the torn strips altogether from the feed mechanism. This would not only tend to defeat the effective promotion of registration but 65 might require readjustment of the strips in

the machine, with consequent loss of time and possible error of the progressive record.

As illustrated, the form-registering feed-arresting apertures are in duplicate for each form, one of the apertures 5 being on one side of the central longitudinal line of the strip and the other similar aperture 5 being on the opposite side of said central line, the two apertures being spaced apart transversely in each strip. By this disposition 75 of duplicate apertures the disc feed mechanism of the machine which coacts along the longitudinally apertured lines is enabled to exert its feeding effect at points sufficiently spaced width-wise of the strip to effect uniform feed of the full width of each strip. Both sides of the strip are advanced simultaneously and both sides of the strip are arrested simultaneously, so as to avoid balling up, curling or tearing of the strips occasioned by providing the apertures near but 80 one edge of the strips.

In order that the strips 2, 3, and 6 shall fold readily at the fold lines they are weakened along such lines and in the present embodiment the strips are perforated for such purpose. As illustrated, the leaves of the pad are substantially equal in length and when in inscribing position the superposed forms and apertures are in registry, respectively. Also at that time the fold lines of the leaves in inscribing position are also in registry or substantially so, and the registry of these lines is promoted by the form-registering apertures, the distance from a fold 95 line of any leaf to the next adjacent form-registering aperture in such leaf being substantially the same in all the sets.

It will be observed that the perforations along the fold lines are so disposed relative 105 to the apertures 5, that at the fold lines strip material remains or is left in longitudinal alignment with the longitudinal series of form-registering apertures. In this wise notwithstanding the apertures provided by the perforations at the fold lines, strip material is there provided for cooperation with the feed wheels of the register so that the advance of the strips is not arrested by these perforations.

In forming the pad the several strips are contiguously assembled in superposition and folded zig-zag, as above described. In the original assembly of unfolded strips care should be taken to have the form-registering apertures of corresponding printed forms as near in registry with each other as possible. Thereupon zig-zag folding is effected on the perforated lines so as to provide the superposed manifolding sets A, B, and C of superposed leaves connected end-to-end. This folding may longitudinally displace the form-registering apertures of one strip relative to the corresponding form-registering apertures of the other strips so 120 125 130

that the form-registering apertures of corresponding superposed forms may not remain in exact registry with each other. But they will be disposed in substantial registry serially one with another in the pad, forming a series of sets longitudinally of the strips, and the displacement just mentioned will be practically constant in amount in each manifolding set throughout the pad. Furthermore, due to the close association of the several strips in the unitary pad, the contiguous superposition of the leaves of each manifolding set, and of the sets themselves one on another, together with the zig-zag folding cooperate to restrain longitudinal displacement of both the leaves and the sets relative to each other and in fact practically prevents displacement, relative to each other in one direction, of the form-registering apertures of any set. In this wise when the machine draws from the pad, as for instance draws the set A to the right in Fig. 1, relative displacement between the apertures 5 of sets A and B is restrained by the interfold at the right hand end of set B and by the effect of the contact between an advancing set and one at rest, and by the effect of the contact between the leaves. Thus there is assurance that, although the form-registering apertures may be displaced from registry relation to each other, such displacement is not apt to be excessive, is at all times restrained, is within the limits of practical utility and whatever be the amount, it is substantially the same throughout the pad. Hence, whatever be the length of the record strips, by the present invention the close registration at inscribing position of the apertures of each manifolding set is effected.

In using the book or pad, the form on the uppermost leaf is filled in by writing, typing, etc., and a copy, or duplication, on the underlying leaves is obtained by interposed carbon sheets or otherwise, thereby providing an original, a duplicate and a triplicate record at one inscription, when three strips are employed and any or all of the inscribed forms may thereupon simultaneously be torn from their record strips along the weakened lines, and the succeeding manifolding set advanced into inscribing position. The forms consist of similar printed matter and spaces left blank for writing, typing, etc., the ultimate object being to feed and superpose printed forms in exact registry so that the inscription added to the original shall be duplicated in its proper position in the spaces provided therefor in the underlying forms. In the interest of accuracy the apertures 5 are punched in the strips during the operation of printing the forms. It will be understood that, in place of separate carbon transfer sheets, the under face of one or more of the record strips may

be coated with transfer material; also that different grades and different colors of paper may be employed, and that one or more of the strips may be transparent.

In one form of autographic register for which the herein described pad is especially suitable as a record strip supply the three strips are simultaneously frictionally gripped between two cooperative feed rolls the rotation of which is adapted simultaneously to advance the three strips from the pad, until one of the rolls enters form-registering apertures 5, thereby releasing the grip thereon, such latter roll being narrow so as to enter said aperture. When the apertures of different strips of the same manifolding set arrive at the narrow feed roll "ad seriatim", as might be the case when longitudinally displaced from registry, the lagging strips are in turn gripped and brought into registry with the other. While this is merely an instance of the application of the invention of the herein described supply pad, it exemplifies the importance of maintaining the form-registering apertures in registration in the pad and of avoiding their longitudinal displacement from registration and especially of avoiding assembly of supply strips in which the displacement of possible registering features is progressive in principle.

Since certain changes may be made in the article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention what I claim as new and desire to secure by Letters Patent, is:

1. A supply pad of the character described including, in combination, a plurality of record strips folded zig-zag, the folds of one interengaged with those of the others so as to provide superposed sets of superposed leaves connected end-to-end, each of said strips having a longitudinal series of transverse weakened lines and of feed-arresting apertures, the apertures of different strips being at such points as to register with each other, in successive longitudinally related sets, with the weakened lines also in registry.

2. A supply pad of the character described, including, in combination, a plurality of record strips folded zig-zag, the folds of one interengaged with those of the others

so as to provide superposed sets of superposed leaves connected end-to-end, each of two or more of said strips having a longitudinal series of printed forms, each of said strips having a longitudinal series of feed-arresting strip-registering apertures, the apertures in the respective printed form strips being in similar fixed relation to the forms.

3. A supply pad of the character described, including, in combination, a plurality of record strips folded zig-zag, the folds of one interengaged with those of the others so as to provide superposed sets of superposed leaves connected end-to-end, each of two or more of said strips having a longitudinal series of transverse weakened lines and of printed forms, each of said strips having a longitudinal series of feed-arresting strip-registering apertures, the apertures in the respective printed form strips being in similar fixed relation to the forms and also being at such points that those in one strip register with those in the other strip, in successive longitudinally related sets, when the weakened lines are in registry.

4. A supply pad of the character described, including, in combination, a plurality of record strips folded zig-zag, the folds of one interengaged with those of the others so as to provide superposed sets of superposed leaves connected end-to-end, each of two or more of said strips having a longitudinal series of printed forms, each of said strips having a longitudinal series of feed-arresting strip-registering apertures, the apertures in the respective printed form strips being in similar fixed relation to the forms, longitudinal displacement of said apertures from registration in the pad being substantially constant in amount for each manifolding set of forms.

5. A supply pad of the character described including, in combination, a plurality of record strips folded zig-zag, the folds of one interengaged with those of the others so as to provide superposed sets of superposed leaves connected end-to-end, each of said strips having a longitudinal series of transverse weakened lines and of feed-arresting apertures, the apertures of different strips being clear of the fold lines at the ends of the pad and at such points as to register with each other, in successive longitudinally related sets, with the weakened lines also in registry.

6. A supply pad of the character described, including, in combination, a plurality of record strips folded zig-zag, the folds of one interengaged with those of the others so as to provide superposed sets of superposed leaves connected end-to-end, each of two or more of said strips having a longitudinal series of printed forms, each of said strips having a longitudinal series of feed-arresting strip-registering apertures, the ap-

ertures in the respective printed form strips being in similar fixed relation to the forms, said apertures being clear of the fold lines, the fold lines being perforated to weaken the same, the perforations being disposed to leave strip material at the fold lines in longitudinal alignment with the series of apertures.

7. A supply pad of the character described, including, in combination, a plurality of record strips folded zig-zag, the folds of one interengaged with those of the others so as to provide superposed sets of superposed leaves connected end-to-end, each of two or more of said strips having a longitudinal series of printed forms, each of said strips having a longitudinal series of feed-arresting strip-registering apertures, the apertures in the respective printed form strips being in similar fixed relation to the forms, the apertures in each set of leaves being substantially in registry and disposed in the pad opposite a continuous portion of the next adjacent superposed set of leaves, whereby the outermost leaf of one set of leaves may be seen through the apertures in the next adjacent set.

8. A supply pad of the character described including, in combination, a plurality of record strips folded zig-zag, the folds of one interengaged with those of the others so as to provide superposed manifolding sets of superposed leaves connected end-to-end, two or more of said strips having a longitudinal series of printed forms, each of said strips having a longitudinal series of feed-arresting apertures, the said apertures in one form strip being in the same fixed relation to the forms thereon as in the other form strip, the said apertures of each manifolding set being in substantial registry in the pad and clear of the fold lines, longitudinal displacement of said apertures from registration in the pad being substantially constant in amount for each manifolding set of forms, the fold lines being perforated to weaken the same, the perforations being disposed to leave strip material at the fold lines in longitudinal alignment with the series of apertures.

9. A supply pad of the character described including, in combination, a plurality of record strips folded zig-zag, the folds of one interengaged with those of the others so as to provide superposed manifolding sets of superposed leaves connected end-to-end, two or more of said strips having a longitudinal series of printed forms, each of said strips having a longitudinal series of feed-arresting apertures, the said apertures in one form strip being in the same fixed relation to the forms thereon as in the other form strip, the said apertures of each manifolding set being in substantial registry in the pad and clear of the fold lines, lon-

gitudinal displacement of said apertures from registration in the pad being substantially constant in amount for each mani-folding set of forms, the fold lines being perforated to weaken the same, the perforations being disposed to leave strip material at the fold lines in longitudinal alignment with the series of apertures, the said aper-

tures in each set of leaves being disposed in the pad opposite a continuous portion of the next adjacent superposed set of leaves whereby the outermost leaf of one said set may be observed through the apertures in the next adjacent set.

WILLIAM J. WISWALL.
